ABSTRACT OF THE DISCLOSURE

A pattern font of type is provided whereby a single, double or triple thickness letter may be engraved by using the single pattern font. The stylus of a conventional engraving machine is used to trace the desired thickness letter from the pattern font of type, and a remote engraver is utilized to engrave the letter having the desired thickness.

The present invention relates to a font of type and more particularly to a pattern font of type wherein a single, double or triple thickness letter can be engraved by using the pattern font.

In the use of conventional engraving machines, patterns are provided which are followed by the stylus of the engraving machine. The pattern followed by the stylus is transmitted to an engraver which is at a remote location. The engraver will engrave the pattern onto any desired object, such as a tray, large flatware, trophies, etc. There has not been, heretofore, provided a single pattern font of type which would permit the operator of the engraving machine to selectively engrave a single, double or triple thickness letter.

It is an object of the present invention to provide a pattern font of type whereby a single, double or triple thickness letter can be selectively engraved by using the single pattern font.

It is another object of the present invention to provide a pattern font of type whereby letters or numerals can be engraved in single, double or triple thickness by use of the single pattern font.

It is still another object of the present invention to provide a pattern font of type whereby a single, double or triple thickness letter or numeral can be engraved by use of conventional engraving apparatus.

It is another object of the present invention to provide a versatile pattern font of type which will substantially reduce the number of different fonts which must be stored to permit varying thickness letters or numerals to be engraved.

Other objects will appear hereinafter.

The above and other objects are accomplished by means of the present invention. A pattern font of type is provided whereby a single, double or triple thickness letter can be engraved by using the pattern font. The stylus of a conventional engraving machine may be used to pick off the desired thickness letter or numeral from the pattern font and transmit the same to a remote engraver. The engraver will engrave the selected letter or numeral on an object such as a tray, trophy or the like.

The pattern font of type is provided with a plurality of grooves therein. The grooves in the pattern font of type will define a triple thickness letter. Some of the grooves will also define a single thickness letter. Some of the grooves will also define a double thickness letter. The single and double thickness letters will be defined by separate and distinct grooves which cooperate together to define the triple thickness letter. The single and double thickness grooves will be positioned with respect to each other to define the triple thickness letter.

For the purpose of illustrating the invention, there is shown in the drawings a form which is presently pre-

2

ferred; it being understood, however, that this invention is not limited to the precise arrangements and instrumentalities shown.

FIG. 1 is a plan view of a font of type having letters of single thickness shown in the left, center and right positions;

FIG. 2 is a plan view of a font of type having letters of double thickness shown in the left, center and right positions;

FIG. 3 is a plan view of a font of type having letters of triple thickness shown in the left, center and right positions;

FIG. 4 is a perspective view of a conventional engraving machine which can be used with the present invention;

FIG. 5 is a perspective view of a pattern font of type in accordance with the present invention;

FIG. 6 is a section view taken along the line 6—6 of FIG. 5;

FIG. 7 is a plan view of a triple thickness engraving produced by using the pattern font of type of the present invention;

FIG. 8 is a plan view of a double thickness engraving produced by use of the same pattern font of type to produce the triple thickness engraving of FIG. 7; and

FIG. 9 is a plan view of a single thickness engraving produced by use of the same pattern font of type used to produce the triple thickness engraving of FIG. 7 and the double thickness engraving of FIG. 8.

Referring now to the drawings in detail, wherein like numerals indicate like elements throughout the several views, there is shown in FIG. 4 a conventional engraving machine designated generally by the reference numeral 10.

The engraving machine 10 includes a frame which includes a support member 12 on the left side of FIG. 4 supported by legs 14. Member 12 is coupled to the legs 14 by C-shaped adapters 16. On the opposite side of the frame, there is provided a second support member 18.

Member 18 is supported by legs 20 and coupled thereto by C-shaped adapters 22.

The legs 14 and 20 are interconnected by a hub 32 by means of webs 24, 26, 28 and 30. The hub 32 supports a vertical shaft 34 for up and down and rotary movement. Since the engraving machine 10 is conventional, it need not be described herein in detail. If desired, the engraving machine may be of the type disclosed in U.S. Pat. 2,426,156.

A pattern plate or pattern font of type 36 is removably supported on the member 18 and contains the printed matter to be engraved on an object. The pattern plate 36 may be composed of any suitable material such as metal. The plate may be approximately $\frac{1}{16}$ of an inch thick. As shown in FIGS. 1-3, this invention is directed primarily to the engraving of letters in either left, center or right positions in either single, double or triple thickness.

FIG. 1 shows letters in the left, center and right position of single thickness. FIG. 2 shows letters in the left, center and right position of double thickness. FIG. 3 shows letters in left, center and right position of triple thickness. It is to be appreciated however that this invention is not limited to the engraving of letters and it is also applicable to the engraving of numerals of single, double or triple thickness.

A stylus 38 is adapted to trace the printed matter on the pattern plate 36. Stylus 38 depends from a pantograph 40. The operation of the pantograph 40 is well known in the art and need not be described herein. An engraving tool 42 is supported by the pantograph and is provided with a lever 46 which permits selective lowering of the engraver 42. One end of the pantograph 40 is con-

nected to a carriage 48. The carriage 48 is movable by means of a handle 50 to cause the carriage 48 to reciprocate toward and away from the support 18. The engraver 42 is adapted to engrave printed matter traced by the stylus 38 onto an object 44. The object 44 may be a tray, trophy, medal, etc.

Referring now to FIGS. 5 and 6, the pattern plate of font of type 36 is provided with a plurality of grooves 52, 54 and 56. The grooves 52, 54 and 56 define a triple thickness letter which may be traced by the stylus 38 to engrave the representation of a triple thickness letter 60 on an object 58 (FIG. 7). The grooves 54 and 56 may be followed by the stylus 38 to engrave the representation of a double thickness of the same letter 64 on object 62 (FIG. 8). The groove 52 may be followed by the stylus 38 to engrave the representation of a single thickness of the same letter 68 on an object 66 (FIG. 9). The grooves may be approximately $\frac{1}{64}$ of an inch in depth.

For ease of operation, the groove 52 may be of one color, such as black, whereas the grooves 54 and 56 may be of another color, such as red. Hence, an operator of the engraving machine 10 will be able to merely follow a color code instruction as to what type of letter is to be engraved on an object, such as object 44.

Referring now to FIGS. 5-9, it is to be noted that the grooves 54 and 56 are positioned with respect to the groove 52 to permit an attractive triple thickness engraving such as indicated by the reference numeral 60. Alternatively, a double thickness letter can also be traced by having the stylus follow the grooves 54 and 56. Alternatively, a single thickness letter generally indicated by the reference numeral 68 can be traced by having the stylus follow the groove 52. The pattern font consists of any desired indicia, such as letters or numerals. There will normally be only one indicium on each pattern font.

It is to be noted that the single pattern font 36 provides great versatility and eliminates the necessity of providing numerous pattern fonts. In the past, it has been necessary to provide distinct pattern fonts to permit engravings 60, 64 and 68 to be made. This invention results in the elimination of the need for substantial storage space for numerous pattern fonts and also results in substantial economies, since a single pattern font rather than three pattern fonts may be purchased.

As stated, the pattern font may contain any desired indicia such as letters or numerals.

The present invention may be embodied in other specific forms, without departing from the spirit or essential attributes thereof.

I claim:

1. A pattern font of type for use with an engraving machine comprising a pattern font having a plurality of grooves therein, said grooves defining a single thickness representation of indicium and a separate and distinct double thickness representation of said indicium, said single and double thickness indicium grooves being positioned with respect to each other to define a triple thickness representation of said indicium whereby a stylus of an engraving machine may trace the grooves on the pattern font of type to permit an engraving tool to selectively

form, at a remote location, one of said single, double and triple thickness representation of said indicium.

2. A pattern font of type as set forth in claim 1, wherein in said pattern font is composed of metal, is approximately $\frac{1}{16}$ of an inch thick, and said grooves extend approximately $\frac{1}{64}$ of an inch into the upper face of said pattern font.

3. A pattern font of type as set forth in claim 1, wherein in the grooves defining the single thickness indicium are of a first color and the grooves defining the separate and distinct double thickness indicium are of a second color, said first and second colors being different.

4. A method of engraving indicium including the steps of providing a pattern font, providing grooves defining a single thickness indicium on the pattern font, and a double thickness representation of the same indicium on the pattern font, providing the single and double thickness representation in a spaced relationship so that the grooves define a triple thickness representation of the same indicium, using a stylus of an engraving machine to selectively trace the grooves on the pattern font to selectively trace one of the single, double and triple thickness indicium.

5. A method as set forth in claim 4 including the step of providing an engraver at a remote location to repeat the indicium traced by the stylus.

6. A method as set forth in claim 4 including the steps of providing sufficient pattern fonts to permit selective engraving of one of a left, center and right position indicium in one of single, double and triple thickness.

7. Apparatus including an engraving machine having a stylus and an engraving tool, a support surface on said engraving machine, a pattern font of type adapted to be supported by said support surface, said pattern font having a plurality of grooves therein, said grooves defining a single thickness representation of a letter and a separate and distinct double thickness representation of said letter, said single and double thickness letter grooves being positioned with respect to each other to define a triple thickness representation of said letter so that said stylus may trace the grooves on the pattern font of type to permit said engraving tool to selectively form, at a remote location, one of said single, double and triple thickness representation of said letter.

8. A pattern font of type as set forth in claim 7, wherein in the grooves defining the single thickness letter are of a first color and the grooves defining the separate and distinct double thickness letter are of a second color, said first and second colors being different.
